DESIGN FOR A RACK FOR BREAD OR THE LIKE

Milton Petersen, Omaha, Nebr., assignor to C. E.
Erickson Company, Incorporated, Des Moines,
Iowa, a corporation of Iowa

Application February 6, 1936, Serial No. 60,999

Term of patent 7 years

To all whom it may concern:

Be it known that I, Milton Petersen, a citizen of the United States and a resident of the city of Omaha, county of Douglas, and State of Nebraska, have invented a new, original, and ornamental Design for a Rack for Bread or the like, of which the following is a specification, reference being had to the accompanying drawing, forming part thereof.

Figure 1 is a perspective view of a rack for bread or the like illustrating my new design.

Figure 2 is a top plan view of the same.
Figure 3 is a side elevational view thereof; and
Figure 4 is an end elevational view thereof.
Figures 2, 3, and 4 are on a reduced scale.

I claim:
The ornamental design for a rack for bread or the like, substantially as shown and described.

MILTON PETERSEN.
